UNITED STATES PATENT OFFICE.

LEWIS L. SCOTT, OF ST. LOUIS, MISSOURI.

METHOD OF IGNITING HYDROCARBONS.

1,307,214.

Specification of Letters Patent. Patented June 17, 1919.

Application filed February 14, 1918. Serial No. 217,263.

To all whom it may concern:

Be it known that I, LEWIS L. SCOTT, a citizen of the United States, residing in the city of St. Louis, Missouri, have invented a new and useful Improvement in Methods of Igniting Hydrocarbons, of which the following is a specification.

My invention relates to the burning of heavy oils which are practically non-volatile at normal temperature; and has for its object to provide a method of instantaneous ignition of heavy oils at their normal temperature, by electrical means, such as an electric spark.

This invention can be used in connection with any heat absorbing medium such for example, as a steam generator used in steam automobiles.

I have found that heavy liquid hydrocarbon can be completely burned, without pre-heating, from a normal temperature condition by finely dividing the liquid fuel and mixing it with the proper amount of air to support combustion.

It is a well known fact that a completely combustible mixture of heavy hydrocarbon fuel and air at normal temperature, cannot be ignited by an electric spark of normal size. It is also well known that a finely divided hydrocarbon fuel, such as kerosene, can be ignited at normal temperature by an electric spark if said fuel is mixed with air in such proportion that the mixture is rich in hydrocarbon and therefore incompletely combustible.

I am aware of the fact that it is old to finely divide heavy hydrocarbon fuel by atomizing said fuel with high pressure air (said mixture being rich in hydrocarbon) and igniting the rich mixture by an electric spark, and then adding a sufficient amount of air to the ignited mixture to support complete combustion. I am also aware of the fact that it is old to ignite (by an electric spark) a finely divided mixture of heavy fuel and air (rich in hydrocarbon) which mixture is atomized by high pressure air, and to ignite a completely combustible mixture from the flame of said rich mixture, and to then shut off the rich mixture flame after a certain period of time.

Such arrangements take a considerable amount of power for their operation, because an air compressor for furnishing high pressure air is required to finely divide the liquid fuel, and a low pressure blower is also re-

quired if any considerable amount of heat is to be generated. In addition to the excessive power required for such devices, they give off undesirable smoke and soot at times. 60

The object of my invention is to provide a method of instantly igniting heavy hydrocarbon fuel and air in such a manner that no smoke or soot will be produced and where only a small amount of power is required, as 65 compared to the above mentioned methods.

In the accompanying drawings,

Figure 1, is a diagram of an apparatus for carrying out my improved method, as applied to a steam generator. 70

Fig. 2 shows another form of fuel burning apparatus for carrying out my improved method.

Referring to the drawings, 1 represents the coils of a steam generator of the semi-flash type, 2 is the water inlet to the coils 1 and 3 is the steam outlet pipe. 4 is a heat insulating inclosure for coils 1 which has the combustion chamber 5 formed at its lower portion. 6 is a rotating member which is formed with the cup 7 on its outer periphery. 8 is a central hub which is joined to the cup ring 6 by the open fan blades 9. The numeral 10 represents an electric motor which drives the rotary member 6 through 75 the shaft 11. Liquid fuel is supplied to the cup 7 from the fuel tank 12, in the following manner: A plunger pump 13, which is supplied with the usual check valves 14, is operated by the motor 10 through the shaft 15, which shaft carries the worm 16; said worm 16 drives the worm wheel 17; said worm wheel 17 carries the crank pin 18, which crank pin is connected to plunger of the pump 13 by the connecting rod 19. The suc- 80 tion pipe 20 from the pump 13 connects to the fuel tank 12; the discharge pipe 21 from the pump 13 connects to a small tank 22. The pipe 23 is an overflow from the small tank 22 back to the main fuel tank 12 so that 85 fuel will be kept at a constant level in the tank 22. The pipe 24 supplies fuel by gravity from the small tank 22 to the rotating cup 7. A solenoid valve 25 is placed in the fuel line 24, said solenoid being connected in 90 series with the electric motor 10 so that when said motor 10 is in operation the fuel valve, operated by the solenoid 25, will be open so that fuel can flow from the tank 22 to the cup 7. The battery 26 supplies electric cur- 95

rent for operating the motor 10 and solenoid 25. The wire 27 connects to the negative 100 105 110

side of the battery 26 and runs to the manually operated switch 28 and from said switch 28 the wire 27 runs to one side of the motor 10. The wire 29 is connected to the solenoid 5 25 and runs from the solenoid to the insulated stationary contact screw 30. The numeral 31 represents a Bourdon tube which is connected to the steam pressure in the generator 1 by the pipe 32. When a predetermined pressure is created in said Bourdon 10 tube, said tube will move the spring held lever 33 out of contact with the insulated screw 30. As the wire 34 connects the positive side of the battery 26 to the lever 33, the 15 electric circuit will be broken by the action of the Bourdon tube as above described. When the electric circuit is broken, either by the switch 28 or by action of the Bourdon tube, the motor 10 will not operate and the 20 solenoid operated valve 25 will be closed, so that no fuel will flow from the tank 22 to the rotating cup 7.

The numeral 35 represents an air blower which is operated by the motor 10. The 25 pipe 36 delivers air from the blower 35 to the chamber 37 in which chamber the member 6 revolves. It will be noted that a portion of the air, from the blower 35 to the combustion chamber 5, passes through the 30 center fan blades 9 (of the rotating member 6) and the balance of the air from the blower 35 passes through the space between the rotating member 6 and the wall 38. It will be seen that as the fuel flows into the rotating 35 cup 7, said fuel will be atomized by centrifugal action and that said atomized fuel will be carried to the combustion chamber 5 by the air from the blower which passes between the rotating cup and the wall 38. It 40 will be further seen, that if complete combustion takes place in the chamber 5 and that only a part of the air which goes to said chamber 5, passes through the atomized fuel, said mixture will be (until it meets with additional air) rich in hydrocarbon. As the 45 additional air passes through the fan blades 9, complete combustion will take place in the chamber 5. The rich mixture is ignited by the spark plug 39 which is placed in the zone 50 of said rich mixture. Electric current for the spark plug is furnished from the battery 26 through a common spark coil of which 40 is the primary winding and 41 the secondary winding.

55 In Fig. 2, I show another form of apparatus for carrying out my improved method. The pipe 42 connects to the air blower 35 and the pipe 43 connects to the combustion chamber 5. The spark plug, fuel tanks and 60 solenoid are the same as shown in Fig. 1. Fuel from the tank 22 is conveyed through the pipe 24 to the pipe 44 which pipe 44 is formed into a ring and is placed at the throat of the Venturi tube 46. Said pipe 44 has 65 numerous small openings communicating

with the interior of the Venturi tube 46. The numeral 47 represents a tube which is positioned inside of the Venturi tube 46 so as to divide the air passing from the blower 35 to the combustion chamber 5. A part of 70 the air will pass through the central portion of the tube 47 and the balance will pass through the space between the Venturi tube 46 and the tube 47. The tube 47 is preferably formed with spiral teeth on its outside 75 periphery so that the air passing between the Venturi tube 46 and the tube 47 will be given a rotary motion and will be retarded somewhat in velocity.

It will be noted that the spark plug 39 is 80 located in the zone where a rich mixture will be produced, and that said spark plug will ignite said finely divided rich mixture, and that the air passing through the center of the tube 47 will join with the ignited mixture, which is rich in hydrocarbon, so as to 85 form a completely combustible mixture.

It will be noted that I do not use air pressure to atomize or break up the fuel into small particles, and that I do not use a 90 starter burner, which must be shut off after a predetermined period of operation. When a starter burner is in operation complete combustion can not take place, and there will be smoke and soot as long as it is in 95 operation. It will also be noted that the power required to atomize the fuel is very slight as compared to atomizing said fuel by air suction.

By the use of the term "low pressure" as 100 applied to the air employed, I refer merely to such pressure as will propel the air in the form of a current. In practice, this is about one-half inch water pressure.

By defining the fuel as being "mechanically finely divided and projected in the form of a spray", I refer to such action as will cause the fuel itself to be directly projected in spray form, as distinguished from an aspirating action, which involves acting 110 upon the fuel, as it emerges from an orifice, with high pressure air.

What I claim is:

1. The method of causing combustion of a mixture of liquid hydro-carbon and air at 115 normal temperature, which comprises mechanically finely dividing and projecting in the form of a spray the liquid hydro-carbon, maintaining all the sprayed fuel in an incompletely combustible state until ignition thereof, then electrically igniting said sprayed fuel, and then adding a sufficient amount of air to the ignited fuel to obtain complete combustion.

2. The method of causing combustion of a 125 mixture of liquid hydro-carbon and air at normal temperature, which comprises mechanically finely dividing and projecting in the form of a spray the liquid hydro-carbon, adding air thereto in such proportion 130

that the mixture is incompletely combustible, and is rich in hydro-carbon, maintaining all the sprayed fuel in an incompletely combustible state until ignition, then igniting said mixture and then adding a sufficient amount of air to the ignited mixture to obtain complete combustion.

3. The method of causing combustion of a mixture of liquid hydro-carbon and air at normal temperature, which comprises directly projecting in the form of a spray the liquid hydro-carbon unmixed with air, producing a current of air at low pressure, dividing said air current, passing one part thereof into the zone of the finely divided hydro-carbon in such proportion that the mixture is incompletely combustible, maintaining all of the sprayed fuel in an incompletely combustible state until ignition, then igniting the aforesaid mixture, and passing the other part of said air current into the zone of said ignited mixture beyond the point of ignition thereof to secure complete combustion.

4. The method of causing combustion of a 25 mixture of liquid hydro-carbon and air at normal temperature, which comprises mechanically finely dividing and projecting in the form of a spray the liquid hydro-carbon, producing a current of air at low pressure, dividing said air current, passing one part thereof into the zone of the finely divided hydro-carbon in such proportion that the mixture is incompletely combustible, maintaining all of the sprayed fuel in an 35 incompletely combustible state until ignition, then igniting the aforesaid mixture, and passing the other part of said air current into the zone of said ignited mixture beyond the point of ignition thereof, to se- 40 cure complete combustion.

In witness whereof I have hereunto set my hand this 12th day February, 1918.

LEWIS L. SCOTT.
